PC(57) **CLAIM**

The ornamental design for a travel bottle cap, as shown and described.

DESCRIPTION

FIG. 1 is a front perspective view showing our new design for a travel bottle cap,
FIG. 2 is a front view thereof,
FIG. 3 is a rear view thereof,
FIG. 4 is a top view thereof,
FIG. 5 is a bottom view thereof,
FIG. 6 is a left side view thereof,
FIG. 7 is a right side view thereof; and,
FIG. 8 is a front perspective view thereof with the lid in a closed position.
The broken lines depict environment and form no part of the claimed design.
